UNITED STATES PATENT OFFICE.

CHARLES F. DENMAN, OF NICHOLASVILLE, KENTUCKY.

TOY.

1,241,937.

Specification of Letters Patent.

Patented Oct. 2, 1917.

Application filed March 6, 1917. Serial No. 152,764.

To all whom it may concern:

Be it known that I, CHARLES F. DENMAN, a citizen of the United States, residing at Nicholasville, in the county of Jessamine 5 and State of Kentucky, have invented new and useful Improvements in Toys, of which the following is a specification.

This invention relates to toys characterized by a movable figure, which in the present instance is a trapeze performer, and it is the object of the invention to provide a simple and amusing toy of this kind which may be manipulated to cause the figure to turn somersaults.

With the object stated in view, the invention consists of a novel combination and arrangement of parts to be hereinafter described and claimed, and in order that the same may be better understood, reference is had to the accompanying drawing forming a part of this specification.

In the drawing,

Figure 1 is a perspective view of the toy, and

Fig. 2 is a front elevation thereof.

Referring specifically to the drawing, 5 denotes a base board which supports the toy, and from this board rise, to a suitable height, two laterally spaced uprights 6 supporting at their upper ends a shaft 7 having one end provided with a hand crank 8. The shaft extends between the uprights and the latter have bearing apertures in which the shaft is journaled. From the shaft 7 is suspended a trapeze bar 9, said bar being carried by the ends of two laterally spaced wires 10 fixed to the shaft. Thus it will be seen that when the shaft is rocked by means of the hand crank 8, the trapeze bar is 40 swung back and forth.

On the trapeze bar 9 is mounted a jointed figure representing a trapeze performer composed of a body portion 11 having joint-

ed arms 12 and legs 13. The bar 9 passes straight through the body portion 11 of the figure, and said figure is balanced on the bar so that it is normally in upright position. The figure is pivoted on the trapeze bar so that it is free to revolve, the bar passing loosely through the body portion 11. 50

Below the trapeze bar 9, a cross rod 14 extends between the uprights 6, said cross rod being positioned to intercept the figure carried by the trapeze bar, and serving as an abutment to cause the same to revolve. 55

In operation, the trapeze bar 9 is swung to and fro by means of the hand crank 8, and when the figure carried by the bar strikes the cross rod 14, it makes a complete turn, simulating the movement of a trapeze 60 performer turning a somersault.

I claim:

1. A toy comprising a figure, a swinging support on which said figure is free to revolve, and an abutment in the path of the figure for causing the same to revolve when striking the abutment. 65

2. A toy comprising a pair of laterally spaced uprights, a transverse shaft carried by the uprights, a trapeze bar suspended 70 from the shaft to swing when said shaft is rocked, a figure pivotally mounted on the trapeze bar, and an abutment in the path of the figure for causing the same to revolve when striking the abutment. 75

3. A toy comprising a pair of laterally spaced uprights, a transverse shaft carried by the uprights, a trapeze bar suspended from the shaft to swing when said shaft is rocked, a figure pivotally mounted on the 80 trapeze bar, and a cross bar extending between the uprights and positioned to intercept the figure and to revolve the same when struck thereby.

In testimony whereof I affix my signature. 85
CHARLES F. DENMAN.
